UNITED STATES PATENT OFFICE.

HUMPHREY G. GRIFFITH, OF INDIANAPOLIS, INDIANA.

SIGNAL-LANTERN.

SPECIFICATION forming part of Letters Patent No. 449,736, dated April 7, 1891.

Application filed November 13, 1889. Serial No. 330,180. (No model.)

To all whom it may concern:

Be it known that I, HUMPHREY G. GRIFFITH, of Indianapolis, in the county of Marion and State of Indiana, have invented certain new and useful Improvements in Signal-Lanterns; and I do hereby declare the following to be a full, clear, and exact description of the invention, such as will enable others skilled in the art to which it pertains to make and use it, reference being had to the accompanying drawings, which form part of this specification.

My invention relates to an improvement in signal-lanterns, and which is intended as an improvement upon my patent of August 6, 1889, No. 408,614; and it consists in the construction and arrangement of parts which will be more fully described hereinafter, and particularly pointed out in the claims.

The objects of my invention are to produce a signal-lantern which is so constructed that a revolving shutter placed within the lantern can be revolved by either a pressure of the hand upon the handles or the bails, and by which it is carried around, and thus either allow the light to pass through the lens or window or to shut it out at will; to make the center of the lantern-case and revolving shutter spherical, or nearly so, in shape, whereby the shutter is supported within the case and adapted to be easily revolved independent of any other means for doing so; to so construct the bottom of the case that it will receive either a lamp or a candle, and so construct the mechanism connected to the handles and bails for operating the shutter that one can be operated independent of the other.

Figure 1 is a vertical section of a lantern which embodies my invention complete. Fig. 2 is a top plan view of the same. Fig. 3 is a rear elevation. Fig. 4 is a detached side view of the lower portion of the case in which the lamp or candle is placed. Fig. 5 is a detached view of a portion of the spring-actuated operating-shaft, the arms and levers connected therewith, and the operating-handle. Fig. 6 is a top plan view of Fig. 4. Fig. 7 is a vertical section of the lower portion of the case in which the lamp is placed and of the lamp placed therein. Fig. 8 is a top plan view of the lantern, showing the bails raised upward. Fig. 9 is a detached side elevation of the bails, the gear-wheel journaled upon the top of the

case, and the bearings therefor. Fig. 10 is a top plan view of the lantern, showing a slightly-modified form of the manner of attaching the bails to the case. Fig. 11 is an edge view of the connecting-lever, showing the spring and the pivotal pin connected thereto. Fig. 12 is a side elevation of the shutter. Fig. 13 is a detached view of the inner upper end of the operating-handle I', showing a modification in construction from that shown in Figs. 1, 3, and 5.

A represents the body and central portion of the lantern, which is preferably spherical, or nearly so, in shape, as shown, and in which the revolving shutter B is supported, and which corresponds in shape to the shape of the interior of the case A.

C is the chimney, that is secured to the upper portion of the case A, and D is the lamp chamber or case, which is secured to the lower end of the body A. Secured to the top of the chimney is the conical cap F, and directly over this are supported one or more cowls E.

G is the lens or window frame, which is secured to the front of the case A and to which is hinged the door H, in which the lens I is secured in any suitable manner, and to the door H upon the opposite side from the hinge is an ordinary latch J, by means of which the door is fastened.

I preferably, though not necessarily, place the lamp K within a case L, which is slipped up through the open bottom of the lamp chamber or case D. Formed in the center of this lamp-case L and extending upward a suitable distance is the annular flange or ring M.

Secured within the opening which is formed by the annular flange or ring M is a spring N, which bulges inward a suitable distance, as shown. This opening is formed for the purpose of adapting the lantern to receive a candle, which is held therein by the spring N.

While I show a separate case for the lamp and that provided with an opening to receive a candle, it will be readily understood that the bottom of the case D may be closed and its closed end provided with an opening having a spring for retaining a candle and in which event the lamp will be placed in the case A through the door H.

The wall of the chamber D is provided with

the bayonet-slots O, as shown in Fig. 4, in which the bevel-ended projections P pass and which enter perforations made in the ends of the springs Q, that are secured to the outer side of the case D, and by means of which the lamp is secured within the case in the ordinary manner. Where an upwardly-projecting flange M is used, it is necessary to provide the lamp with an opening R, into which 10 this flange extends, as shown in Fig. 7.

Extending out from the back of the case A and secured thereto is the closed frame a, which has its lower end open for the passage of air to the lamp for combustion through 15 the openings S, made in the case A, as shown.

Secured to the frame a is a shield T, which has closed sides and top, but an open bottom, through which air passes to the apertures S.

20 U indicates a collar, which fits in the upper end of the case D and to which the lower end of the shutter B is secured. The upper end of the shutter is secured to the collar V, which is provided with arms W, having a central opening, and secured to the inner side of the chimney C, just above the collar V, are the arms X, also having a central perforation, and through these perforations passes a pivotal bolt or rivet Y.

30 The shutter B is provided with an opening Z through its side, which is brought in and out of register with the lens I by means of a mechanism hereinafter described.

Fastened to the upper and lower right-hand 35 corners of the frame are the bearings A', in which is journaled the spring-actuated operating-shaft B'. The upper end of this shaft extends through its bearing a suitable distance and has rigidly secured thereto at its 40 upper end the lever C'. Loosely jointed to the opposite and inner end of this lever is a curved connecting-bar D', and the opposite end of this connecting-bar is loosely jointed in the slotted end of the pin E', which is rigidly secured to the collar V at the upper end 45 of the shutter and extends through a slot F', made in the chimney C. (Shown by dotted lines in Fig. 1.)

Rigidly secured to the shaft B' near its 50 upper and lower ends are the arms G', which are engaged by the inner end of the levers H', that are loosely placed upon the shaft so as to revolve independent of it, and their outer ends engaged by the operating-handle 55 I', which also revolves upon the shaft independent of it. Instead, however, of having the levers C', they may be omitted and the inner ends of the operating-handle I' turned upwardly and downwardly, respectively, and 60 made to engage the arms G', as shown in the detached Fig. 13; and while I show the pin E secured to the upper collar V and the lever C' secured to the upper end of the shaft B' it will be readily understood that the pin can 65 as well be secured to the lower collar, or to the shutter at any other desirable point, and the lever C' secured to the shaft at a corre-

sponding point, leaving in each case the mechanism exactly as it now is.

Surrounding the shaft B' is the spiral spring 70 J', which has one end turned inward from the shaft and either resting against the case A or secured thereto in any manner, and has its other end secured to or passing through the upper lever H'; or it may rest against the 75 operating-handle I'. This spring keeps the handle I' and the lever C' normally in their respective positions (shown in Fig. 2) and the shutter B normally in the position shown in Fig. 1, with the opening Z out of line with 80 the lens I, thus keeping the light from passing through the lens.

Secured to the case A, just back of the upper and lower left-hand edges, respectively, of the frame a, are the bearings L', in which 85 the ends of the handle M' are journaled. By placing the bearings as here shown it will be seen that the handle is limited in its inward movement by coming in contact with the edge of the frame. When the operating-handle is drawn inward by a pressure of the hand in which both it and the handle M' are grasped, the handle I', lever C', and connecting-rod D' are brought into the position shown by dotted lines in Fig. 2, which partially 90 revolves the shutter B, causes the opening in the shutter to register with the lens, and the light is allowed to pass out through it.

In order to adjust my lantern to be carried and operated by bails attached to its top, as 100 well as by the handles, I secure to the upper end of the shaft B', just above the lever C', a bevel gear-wheel N', with which the bevel-gear O', secured to a shaft P', which is secured in a bearing Q', that is fastened to the 105 casing, as shown, engages. This gear O' is provided with a pin or projection R', which forms a stop, against which the operating-bail S' bears when it is brought toward the center of case, but which allows the bail to 110 drop down without operating the gear.

T' is a second bail, which is journaled between ears that are secured to the top of the case in any suitable manner and in any suitable position. The inner end of the bail S' is 115 journaled upon the shaft P', while its outer end is either journaled between the same ears as the adjacent end of the bail T', as shown in Figs. 2 and 3, or in a separate pair of ears, as shown in Fig. 10.

In Fig. 10 the bail T' is straight across the top of the case, so that the lantern will be balanced and hang straight; but it may be journaled as shown in the other figures. In Fig. 10 the operating-shaft is on the opposite side 125 of the frame a from that shown in Figs. 1, 2, 3, 8, and 9, and which make it adapted to be used by the left hand; but it will be readily seen and understood that it may be placed on either side, and the lantern thus adapted for 130 either the right or left hand.

In Figs. 8 and 9 the bails are shown closed. The bail T' has only a limited movement by having its ends turned, as shown, so as to en-

gage the top of the case; or it may be limited by abutting against a projection upon the ears, as shown in Fig. 8. By this construction when the lantern is being carried by the 5 bails the operating-bail S' is in contact with the projection R' upon the gear O', so that by a pressure of the hand the bail S' is brought nearer to the bail T', which has only a limited inward movement. The gear O', turned, 10 which engages the gear N', partially revolves the shaft and the shutter, whereby the opening in the shutter is made to register with the lens.

While I here show the upper collar pivoted 15 to the arms X, this need not be so, for since the shutter conforms to the inner spherical shape of the lantern-case it will be supported therein, and readily revolves without any such arrangement. By making the shutter spherical 20 in shape that portion of its inner surface opposite the opening will be polished or brightened in any desired manner, thus forming a good reflector and one of the proper shape to concentrate the rays of light and make them 25 stronger.

U' indicates a belt-hook, which is secured at its upper end to the frame a and extends downward, as shown, to near the lower end of the case, and which is hooked over the belt 30 and held in place thereon by the catch V', which rests upon the lower edge of the belt when it is between the hook and the frame.

The curved connecting-rod D' is provided at its inner end adjacent to the slotted pin E' 35 with the spring i, which carries at its outer and free end a pivotal pin that passes through the apertures made in the inner end of the connecting-rod and the slotted outer end of the shutter-pin. By this means the outer 40 end of the connecting-rod can be readily and quickly detached from the shutter-pin, so that the shutter can be operated by the pin alone without the intervention of the mechanism which is attached to the handles.

Having thus described my invention, I 45 claim—

1. In a signal-lantern, the combination of a spherical case adapted to receive a lamp at its bottom, having an opening in its side for 50 the passage of light and a slot in the chimney, a revolving shutter placed therein, having an opening for the passage of light, a pin secured thereto projecting through the slot, an operating-shaft journaled to the rear of the case, a lever secured to its upper end, a rod 55 connecting the inner free end of the lever and the said pin, and a handle journaled upon the shaft and which revolves the shaft, thus causing the shutter to partially turn, substantially 60 as shown and described.

2. In a signal-lantern, the combination of the spherical case adapted to receive a lamp having an opening for the passage of light and a slot, a revolving shutter placed there- 65 in, having an opening for the passage of light, the pin secured thereto which extends through the slot, a shaft journaled to the rear side of

the case, having a lever rigidly secured thereto at its upper end, a connection between the free end of said lever and the said pin, an 70 arm secured to the shaft, and an operating-handle journaled upon said shaft, having its end turned so as to engage with said arm upon the shaft and cause it to turn when the handle is operated, substantially as set forth. 75

3. The combination of the case having an opening for the passage of light and a slot, a revolving shutter placed therein, having an opening for the light, a shaft journaled to the case, a lever rigidly attached thereto, a 80 rod connecting the lever and shutter, a handle journaled upon the shaft, having a limited movement independent of the shaft, so as to cause it to turn, and a spring for returning the shaft to position, substantially as 85 specified.

4. The combination of the case having an opening for the passage of light and a slot, a revolving shutter journaled therein, having an opening for the passage of light, a shaft 90 journaled on the case, a lever rigidly connected therewith at one end and connected at its opposite end by means of a connecting-rod to the shutter through the slot, an arm rigidly attached to the shaft, a handle journaled upon 95 the shaft, and a lever turning upon the shaft, having one end to engage the said arm and its opposite end engaging the handle, whereby the handle is allowed only a limited movement independent of the shaft for the purpose of partially revolving it and operating the shutter, substantially as described. 100

5. The combination of the case having an opening for the passage of light and a slot, a revolving shutter having an opening for the 105 passage of light, a shaft journaled to the case, a lever rigidly attached thereto at one end and being connected by a rod through the said slot to the shutter, a handle journaled upon the shaft, having only a limited movement independent of the shaft, a vertical 110 frame secured to the rear side of the case, and a second handle journaled upon the case and engaging the said frame outside of its bearings, whereby it is limited in movement, so 115 that when the two are tightly grasped the operating-handle is turned, for the purpose described.

6. In a signal-lantern, the combination of the case having an opening for the passage 120 of light and a slot, a revolving shutter journaled therein, having an opening for the light, a vertical shaft journaled to the case, a lever rigidly attached thereto at one end and connected at its opposite end by a connecting- 125 rod to the shutter through the said slot, a gear upon the upper end of said vertical shaft, a bail pivoted to the top of the case, and a gear which engages the gear upon the shaft and which is partially turned by the bail for re- 130 volving the shaft and operating the shutter, substantially as specified.

7. The combination of the case having an opening for the light and a slot, a revolving

shutter journaled therein, having an opening for the light, a vertical operating-shaft journaled to the case, a lever connected to the said shaft, a rod connected to the lever and 5 the shutter through the said slot, a gear upon the upper end of the shaft, a second gear journaled on the case, having a projection and engaging said gear upon the shaft, and a bail pivoted to the case, which engages the said 10 projection upon the gear for the purpose of revolving it, substantially as shown, and for the purpose described.

8. The combination, with a lantern having a lamp-containing case, of a lamp-case adapt-

ed to be detachably secured in the bottom of 15 said lantern, having an aperture provided with an upwardly-extending wall for the reception of a candle, and a lamp placed in the lamp-case, provided with a central opening to receive the said vertical wall, substantially 20 as shown and described.

In testimony whereof I affix my signature in presence of two witnesses.

HUMPHREY G. GRIFFITH.
